BILLFOLD

Lester L. Sherwood, Los Angeles, Calif.

Application February 20, 1943, Serial No. 476,555

4 Claims. (Cl. 150—38)

My invention relates to a folding container composed of flexible material, such as leather or the like, and adapted to be carried in the pocket to serve as a convenient container for paper currency, checks, business cards, stamps, and the like, and the principal objects of my invention are to generally improve upon and simplify the construction of the existing forms of bill folds; further, to provide a bill fold of the character referred to that is wholly devoid of stitching as the medium for maintaining the parts in assembled relation, and further, to provide a bill fold wherein the main body is composed of a single piece of material cut and shaped so that when properly folded, a number of compartments and pockets are formed for the reception of paper currency, checks, cards and the like, and which construction affects a material saving of time, labor and consequent cost of manufacture.

With the foregoing and other objects in view, my invention consists in certain novel features of construction and arrangement of parts which will be hereinafter more fully described and claimed and illustrated in the accompanying drawings, in which:

Fig. 1 is a plan view of the blank section of material that forms the main body of the bill fold.

Fig. 2 is a plan view of especially shaped section of flexible material that serves as a pocket connector for the bill fold.

Fig. 3 is an elevational view of the bill fold in open position, and looking against the inner face thereof.

Fig. 4 is a horizontal section taken on the line 4—4 of Fig. 3.

Fig. 5 is an enlarged vertical section taken on the line 5—5 of Fig. 3.

Fig. 6 is an enlarged vertical section taken on the line 6—6 of Fig. 3.

Fig. 7 is a perspective view of the bill fold in closed position.

Fig. 8 is a plan view of the blank section of material utilized in producing a modified form of the bill fold.

Fig. 9 is an elevational view looking against the inside of the bill fold when opened.

Fig. 10 is a horizontal section taken on the line 9—10 of Fig. 9.

Fig. 11 is an enlarged vertical section taken on the line 11—11 of Fig. 9.

Fig. 12 is an enlarged vertical section taken on the line 12—12 of Fig. 9.

Fig. 13 is a perspective view of the modified form of the bill fold in closed position.

Referring particularly to the form of bill fold illustrated in Figs. 1 to 7 inclusive, it will be noted that the main body of the bill fold is formed from a single piece of flexible material, cut to the form as illustrated in Fig. 1. This body includes a back or outer wall member 10 of rectangular shape and having a length approximately twice its width, and projecting from the upper edge of this back wall section is a back wall lining member 11 that is adapted to fold over onto the inner face of the back wall 10, and the space 12 between the walls 10 and 11 provides a secret pocket for the reception of currency, checks and the like.

Projecting from the ends of back wall member 10 are substantially square wall members 13 which when the bill fold is folded into proper shape for use, form the front walls of the side pockets of said bill fold. Projecting outwardly from the outer edges of the members 13 are short tabs 14, and projecting from the lower edges of said members 13 are short tabs 15.

Projecting upwardly from the upper edges of the members 13, beyond the ends of member 11, are substantially rectangular members 16 which combine with other parts of the structure in forming the side pockets, and projecting from the upper edges of said members 16 are tabs 17. Projecting downwardly from the lower edge of the central portion of back wall member 10 is a small rectangular tab 18 which when the bill fold is made up for use is secured by cement, or otherwise, to the inner face of member 10, thus, forming a reinforcement in the lower end of the medial line on which said back wall member folds.

Depending from the lower edge of back wall member 10 to the sides of tab 18 are substantially rectangular members 19 which combine with other parts of the structure forming the side pockets of the bill fold.

Projecting from the outer ends of the wall members 19 are short tabs 20. When the parts of the body of the bill fold, as just described, are folded to proper shape, said walls and parts fold along the dotted lines *a* so that said bill fold has the appearance as illustrated in Fig. 3, and when the bilateral portions of the bill fold are brought together in full closed position, the walls 10 and 11 fold on the centrally arranged dotted line *b*, Fig. 1, so that the bill fold has the appearance as illustrated in Fig. 7.

When folded, the lining wall 11 is positioned

against the front face of the back wall 10 with its lower edge overlying the tab 18 which is cemented to the front face of said back wall 10, and the walls 13, 16 and 19 are now folded over onto the end portions of the back wall 10 and lining wall 11 so that walls 13 become the outer walls of the pocket with the walls 16 extending downwardly immediately in front of the end portions of the lining wall 11, and with the tabs 17 extending upwardly between the lower portions of lining wall 11 and the back wall 10.

The walls 19 extend upwardly between the front walls 13 and the walls 16 with the tabs 20 on the ends of said walls 19 extending between the end portions of the lining wall 11 and back wall 10. (See Fig. 4.) The tabs 14 on the end walls 13 are folded inwardly so as to lie behind the inner edges of the walls 19 and the tabs 15 on the lower edges of walls 13 are folded upwardly so as to lie behind the lower portions of said walls 13 and provide finished lower edges therefor. It is to be noted that the pocket between walls 13 and 19 is closed at top and both ends with flap 16 extending a short distance upwardly into said pocket.

In the event that it is desired to carry an identification card, driver's license, or the like with the face exposed, a square "window" may be cut in wall 13 as shown by dotted lines in Fig. 3 and the card to be displayed, is inserted through the bottom of the pocket behind said wall and said card being retained in said pocket, by flap 15 that passes beneath its lower edge.

To connect the side pocket structures just described, a connector wall 21 is formed from a single piece of leather, or the like, substantially rectangular in shape, as illustrated in Fig. 2, has its end portions positioned between the walls 16 and 19 as illustrated in Figs. 4, 5 and 6 and the central portion of this connector wall extends across the opening between the inner ends of the pocket forming walls as illustrated in Fig. 4.

The space 22 between the walls 16 and lining wall 11 provides a pocket for receiving paper currency, checks and the like and the spaces between the walls 16, 19 and the end portions of connector wall 21 provide pockets for the reception of cards, stamps and the like.

The tabs 14, 15, 17 and 20 are effective in maintaining the various walls forming the pockets in their proper folded positions, and at the same time said tabs materially reenforce and stay the ends, corners and edges of the pocket portions of the bill fold.

Figs. 3 and 4 show the bill fold open in order to give ready access to the various pockets therein, and Fig. 7 shows the bilateral portions of the bill fold folded together so as to enable the bill fold to be conveniently carried in the pocket.

In the modified construction of Figs. 8 to 13 inclusive, the blank member that forms the bill fold is cut from a single piece of flexible material such as leather, and comprises a rectangular back wall 25 from the right hand of which projects a tab 26. Projecting from the left hand edge of member 26 projects a substantially triangular wall 27 and projecting from the upper edge of the latter, is a wall member 28 with a flap or tab 29 projecting from its upper edge.

Projecting from the upper edge of back wall 25 is a substantially rectangular wall 30 and projecting from the lower edge of said wall 25 is a similar wall 31. Projecting from the left hand end of wall 31 is a tab 32 and formed between the lower edge of the central portion of wall 25 and

the upper edge of the central portion of wall 31 is a short horizontally disposed slit 33.

The various walls and tabs of this construction are foldable on the dotted lines x , and the walls 25, 30 and 31 are foldable on a medial line z when the bilateral parts of the structure are folded into closed position so as to be carried in the pocket. (See Fig. 13.)

When the blank section of material constructed as described is folded to form the bill fold, wall 30 is folded downwardly so as to occupy a position in front of wall 25, with tab 26 folded over into the front face of the end portion of said wall 30. Wall 31 is now folded upwardly onto the front face of wall 30 with the right hand end of said wall overlying tab 26 and with the tab 32 on the left hand end of wall 31 projecting behind the left hand end of wall 30.

Triangular wall 27 is folded inwardly so as to overlie the upper left hand end portion of wall 31 as seen in Figs. 9 and 13 with wall 28 extending downwardly between the left hand portions of walls 30 and 31 and with tab 29 extending upwardly between the lower portions of wall 30 and wall 25. (See Fig. 11.)

A narrow portion of wall 31 between the slit 33 and the upper edge of said wall is crimped outwardly as designated by 34 in order that said wall will fold properly without bulging when the bilateral portions of the bill fold are closed as illustrated in Fig. 13.

When this form of bill fold is opened to give access to the pockets therein, the parts thereof occupy the positions as illustrated in Figs. 9 and 10 with the pocket between the walls 25 and 30 open along the top and the pocket between the wall 30 and 31 open at the top and at the right hand end. To completely close the bill fold so that the same may be conveniently carried in the pocket, the right hand portion thereof is swung forwardly and downwardly with respect to the left hand portion in order that the upper right hand corner of the body may be inserted beneath the triangular wall 27, and thus the bilateral parts of the structure are securely mounted in closed position.

Among the particularly desirable features of my invention are the one piece structure of the bodies forming the bill fold, the entire absence of stitching, stapling and like fastening means and the integral tabs and extensions which interlock the various walls and partitions, and at the same time, materially reenforce and stay the ends and corners of the bill fold.

The stitchless feature of the bill fold is particularly advantageous inasmuch as it affords a material saving of time, labor and consequent expense in production costs.

Thus, it will be seen that I have provided a bill fold that is simple in construction, inexpensive of manufacture, and very effective in performing the functions for which it is intended.

It will be understood that minor changes in the size, form and construction of the various parts of my improved bill fold may be made and substituted for those herein shown and described without departing from the spirit of my invention, the scope of which is set forth in the appended claims.

I claim as my invention:

1. A bill fold formed in a single piece from flexible material and comprising a back wall, a back wall lining integral with the upper edge of said back wall, pocket forming walls integral with the ends of said back wall, pocket partition walls

formed integral with the upper edges of said pocket forming walls, pocket partition walls formed integral with the lower edge of said back wall and tabs formed integral with the ends of the pocket forming walls that project from the ends of the back wall, which tabs are folded inwardly behind the inner ends of the pocket partition walls which are formed integral with the lower edge of said back wall.

2. A bill fold as set forth in claim 1 and with tabs formed integral with the upper edges of the pocket partition walls which are integral with the upper edge of said back wall, which tabs are folded into position between the end portions of the lower edge of said back wall lining and 10 said back wall.

3. A bill fold as set forth in claim 1 and with 15

5 tabs formed on the outer ends of said pocket forming walls which tabs are folded into position behind the inner ends of the pocket partition walls which are integral with the lower edge of said back wall.

4. A bill fold as set forth in claim 1 with tabs formed on the lower edges of said pocket forming walls which tabs are folded into position between the lower portion of said pocket forming walls and the lower portions of the pocket forming walls which are integral with the lower edge of said back wall and tabs formed on the upper edges of said pocket partition forming walls which last mentioned tabs are folded into position between the back wall and the lower edge of the back wall lining.

LESTER L. SHERWOOD.
